SPRAY VALVE HEAD OR SIMILAR ARTICLE

Manley K. Hardison, Glenview, Ill., assignor to Dupli-
Color Products Company, Inc., Chicago, Ill., a corpora-
tion of Illinois

Filed Jan. 30, 1961, Ser. No. 63,744

Term of patent 14 years

(Cl. D62—2)

FIGURE 1 is a top plan view of a spray valve head or similar article embodying my new design;

FIGURE 2 is a side elevational view thereof;

FIGURE 3 is a front elevational view thereof;

FIGURE 4 is a rear elevational view thereof; and

FIGURE 5 is a transverse vertical sectional view taken along the line V—V of FIG. 1.

The broken line showing of a can is for purposes of illustration only.

I claim:

The ornamental design for a spray valve head or similar article, substantially as shown and described.
